CLAIM

The ornamental design for a cover plate for in-wall mounted electronic component housing, as shown and described.

DESCRIPTION

FIG. 1 is a front perspective view of a cover plate for in-wall mounted electronic component housing showing my new design;

FIG. 2 is a front view thereof;

FIG. 3 is a rear view thereof;

FIG. 4 is a right side view thereof, the left side view being identical thereof; and,

FIG. 5 is a top view thereof, the bottom view being identical thereof.

The inclusion of broken lines as part of the cover plate illustrated in FIGS. 1 through 3 is for the purpose of illustrating environmental structure and forms no part of the claimed design.

The cover plate is used to cover a wall opening and a portion of an in-wall mounted electronic component housing at least partially disposed within the wall opening.
